US00D533590S

(12) **United States Design Patent** (10) **Patent No.:** **US D533,590 S**
Beyer (45) **Date of Patent:** **** Dec. 12, 2006**

(54) **WRITING UTENSIL**

(75) Inventor: **Hans-Juergen Beyer**, Ober-Ramstadt
 (DE)

(73) Assignee: **Senator GmbH & Co KGaA**,
 Gross-Bieberau (DE)

(**) Term: **14 Years**

(21) Appl. No.: **29/218,848**

(22) Filed: **Dec. 9, 2004**

(30) **Foreign Application Priority Data**

Jun. 9, 2004 (DE) 404 03 544

(51) **LOC (8) Cl.** **19-06**

(52) **U.S. Cl.** **D19/49**

(58) **Field of Classification Search** D19/36,
 D19/37, 41-51, 54-57; 24/11 R, 11 F, 11 P;
 401/52, 99, 100, 104, 105, 106, 107, 108,
 401/109, 192, 195

See application file for complete search history.
